COVER FOR RETURN CONVEYER RUNS

Angus Wellesley Duncan, Worcester, England, assignor to The Mining Engineering Company Limited, Worcester, England

Application March 4, 1949, Serial No. 79,700
In Great Britain March 2, 1948

7 Claims. (Cl. 198—184)

1

The advantages of covering in full the return strand of underground belt conveyors used at the working face are such that it is desirable to provide such covering even in thin seams. The difficulty, however, is that inverted trough pressings of the type generally employed are of such a size that moving over the conveyor into the new track as the face advances is laborious and costly. I have previously proposed to split such pressings about their longitudinal axis and to connect these split sections to each other and to the supporting stools, thus retaining the lateral rigidity of the assembled conveyor.

The present invention provides a covered return belt conveyor suitable for use in thin seams, employing cover pressings split longitudinally and so connected to supporting stools that each half of the pressing serves independently to hold the assembled conveyor in lateral rigidity without need for connection to the other half press- 10 ing.

Other parts of the invention serve, in the preferred forms, to eliminate loose belt carrying rollers and minimize the number of component parts to be handled when moving the conveyor to its new location.

The above and other parts of the invention are embodied in a typical preferred form shown by way of example by the accompanying drawings in which:

Fig. 1 is a side elevation,
Fig. 2 a plan view,
Fig. 3 an end view,
Fig. 4 a sectional elevation on line IV—IV of Fig. 1.

Figs. 5 and 6 are respectively a fragmentary sectional elevation and part plan to a larger scale, showing the central part of a stool, and

Fig. 7 shows an example of an alternative form of face-side cover member.

As shown, the supporting stool comprises two portions, the lower of which is fabricated from round section bars having bights forming foot portions extending longitudinally and transversely across the conveyor and upwardly directed members 2 with conical ends joined by vertical side plates 3 welded between the upright portions 2 and carrying the roller 4 for supporting the return belt 5.

The upper portion of the stool comprises a plate 6 running transversely across the conveyor with upward turned welded intermediate side flanges 7 and having the roller 8 for the carrying belt 10 mounted between end flanges 9. A strengthening web 11 is welded on to the plate 55

2

6 transversely under the roller and further webs 12 are welded at right angles to it of such a length and in such a position that pockets are formed between their ends and the side flanges 7 of the plate 6 near the centre line of the conveyor. The corners of the plate 6 are shaped (as indicated at 13, Fig. 2), being recessed, so that the upper portion of the stool and plate 6 thereof at the reduced ends of the latter, can be inserted between the uprights 2 of the lower portion of the stool, being thereby located with the plate 6 resting upon the side plates 3 of the lower portion of the stool.

The inverted trough covering the return belt 15 is divided longitudinally into two separate parts each comprising inwardly extending portions 14, 15 and side members 16 extending downwards to protect the return belt and upwards to protect the carrying belt. These side members may be of any form convenient for their function as face or goaf side plates.

The adjacent edges of the portions 14, 15 may butt along the centre line of the conveyor with the plate turned back in tubular form as shown, 25 or they may be arranged to overlap.

Welded to the side plates 16 at each end is an open socket 17 in a horizontal plane between the belt laps, which fits over the appropriate upright member 2 of the lower stool around which the lower end of the socket is a close fit, but the upper end of the socket is flared in the longitudinal direction and permits slight angular movement in the vertical plane. A member 18, conveniently of round section is welded to each 30 end of the inwardly extending portions 14, 15 and enters into the pocket on the upper portion of the stool formed between the upwardly turned flanges 7 and the web 12 (see Figs. 2, 5 and 6). It will be appreciated that the fitting of only 35 one half section of the cover pressing gives lateral rigidity to the conveyor structure owing to its engagement by peg and socket connection formed by upright ends 2 in vertical sockets 17 at the outer edge and in the pocket between flange 7 and webs 12 near the centre line of the structure and that some measure of vertical flexibility to follow floor irregularities is retained.

Numerous modifications can be devised in which a half cover member engages with a support both near the outer margin and near the centre so as to provide lateral stability while allowing some angular movement vertically.

In a modification of the typical construction described above, the upper portion of the stool may have extended end flanges and a centrally

fitted bracket to mount two rollers in V form should it be desired to trough the carrying belt.

Similarly, the half cover pan on the face side may have only a downwardly extending side plate as in such troughed conveyors it is generally not necessary to have a side plate protecting the carrying belt or as shown in Fig. 7 the side member 16 may be formed of a bent or inverted substantially V-shaped plate welded to an upturned longitudinal outer edge flange of the 10 cover plate 15 and to both sides of a welded ferrule or the like of bent steel plate constituting the socket 17.

It will be observed that the upper part of the stool is readily separable from the lower part 15 upon which it rests and is held in alignment by the engagement of the corners 13 between the upper end portions 2 of the bars. Also, that the upper and lower parts of the stool can respectively 20 carry the carrying belt and return belt rollers fixed therein by split or cotter pins or the like as shown. In this way there are relatively very few separable parts all of size easy to handle; and the lateral alignment of the conveyor is assured as soon as one half of the cover trough 25 is positioned between successive stools, the second half dropping into position without any further adjustment of the location of the stool.

I claim:

1. A covered return belt conveyor having supporting stools comprising foot portions with upright end portions, transverse plates anchored at their ends to adjacent end portions of the stools to unite the same, and cover troughs divided longitudinally at the center line of the conveyor into two separate parts free of connection to each other along said line, said plates being provided with pockets near the center line in which the ends of the cover trough parts are seated and retained to support each independently, the outer edge of each cover trough part being provided with a socket member engaging an upright end portion in line with said pockets and ends of the cover trough parts.

2. A covered return belt conveyor as set forth in claim 1, wherein said sockets are elongated lengthwise of the conveyor to allow angular movement thereof relative to the upright end portions in a vertical plane.

3. A covered return belt conveyor comprising supporting stools including foot portions with upright end portions, transverse plates anchored at their ends to adjacent end portions of the stools to unite the same, and cover troughs divided longitudinally at the center line of the conveyor into two separate parts free of connection to each other along said line, said plates being provided with pockets near the center line in which the ends of the cover trough parts are seated and retained to support each independently, the ends of the cover trough parts are pro-

vided with rigid bars having a projecting end and held longitudinally and transversely in the pockets to give lateral rigidity to the cover trough parts independently, and a socket member is rigid on the outer edge of each of said parts transversely aligned with said pockets and bars seated therein, and engaging over an upright end portion of each supporting stool.

4. A covered return run conveyor comprising a pair of spaced supporting stools each including a transverse support, a cover trough consisting of two longitudinal half parts for individual insertion between the conveyor runs from the opposite sides thereof and removably mounted at their ends on stools, and releasably cooperable connections on said cover parts and said stools giving rigid lateral alignment independently between each cover part and said stools, said connections comprising outwardly disposed connector means centrally located and upwardly disposed connector means laterally located on said stools, and inwardly disposed connector means on the inner corners of said cover parts for cooperating with said outwardly disposed means centrally located on said stools, and downwardly disposed connector means on the outer corners of said cover parts for cooperating with said upwardly disposed means on said stools.

5. Apparatus as in claim 4 wherein the outwardly disposed connecting means on said stools are at approximately cover trough level and comprises pockets open at their ends and top and the inwardly disposed means on the cover parts comprise pins adapted to drop into and engage in said pockets.

6. Apparatus as in claim 4 wherein the stools comprise upper and lower separable parts, the lower part having spaced upwardly extending posts forming said upwardly disposed connecting means, the ends of the upper parts engaging between the upwardly extending posts and resting on the lower portions.

7. Apparatus as in claim 4 wherein the stools comprise upper and lower separable portions, said upper portions each supporting an upper belt carrying roller and the lower portions each supporting a return belt roller.
